UNITED STATES PATENT OFFICE.

WILLIAM H. ALEXANDER, OF PITTSBURGH, PENNSYLVANIA.

RAILWAY CROSS-TIE.

1,094,769.

Specification of Letters Patent. Patented Apr. 28, 1914.

Application filed January 8, 1914. Serial No. 811,031.

To all whom it may concern:

Be it known that I, WILLIAM H. ALEXANDER, a citizen of the United States, residing at Pittsburgh, in the county of Allegheny and State of Pennsylvania, have invented certain new and useful Improvements in Railway Cross-Ties, of which the following is a full, clear, and exact specification.

10 This invention relates to railway cross-ties, and has for its object, among others, to provide a one-piece tie which may be attached to the rails without the use of spikes, bolts or other separate fastenings.

15 Another object is to provide a tie which is strong and durable and yet possesses the resiliency necessary to withstand the pounding of heavy rolling-stock and prevent injury to the mechanism of locomotives, etc.

20 The tie contemplated is made of sheet-metal and is designed to be pressed into the desired shape with a concave under surface which forms an air cushion between it and the roadbed, whereby the resiliency or adapt-

25 ability of the tie to recoil under the pounding of heavy traffic is increased. Being made of sheet-metal, preferably steel, the tie will not require near as much ballast as the old wooden tie or the more recent I-beam

30 metal tie, for the reason that the present tie will lie upon the top of the ballast whereas when the prior forms mentioned are used the ballast must be laid eight or ten inches deeper or thicker in order to fill up

35 around the sides and ends of the ties, even when the thickness of the ballast below the ties is the same as under my present form of tie.

40 A further object of the invention is to provide a tie which although it requires no separate fastenings to secure it to the rails, yet may be connected or fastened thereto and also detached or disconnected therefrom without separating the rails at their joints.

45 Thus, if a tie should become corroded or accidentally broken, it may be readily removed for recoating with a preservative preparation and returned to its place in the track or a new tie substituted without materially disturbing the track or unfastening the joints of the rails. Moreover, the construction of the tie of one piece of metal, including the rail-fastening means, will

50 greatly reduce the danger of accidents due to spreading rails or the decay of wooden

ties. It is a matter of serious concern that the railway tracks in this and other countries have not been strengthened anywhere near in proportion to the increase in weight of the locomotives and rolling-stock put into use in recent years. The use of the ordinary wooden ties which years ago were capable to a certain degree of withstanding the light traffic of that day, is obviously inadequate for the immense locomotives and heavy steel cars used today, and the percentage of accidents will continue to increase as long as the wooden tie is used and the size and weight of the locomotives and rolling-stock is increased. The tendency of the rails being spread in ordinary traffic today, especially on sharp curves, will be immediately apparent when one considers the terrible impact and strain upon the spikes of the outside rails on such curves when said rails are struck by rapidly moving heavy engines and heavily loaded cars. This terrible impact due to the weight and momentum of the trains as their course is changed by the curve in the track, will press the outside spikes a little bit at a time from the rails, until the gage is partially destroyed, so that each heavily loaded train that passes widens it, until finally the wheels drop in and there is a fearful wreck. An important object of this invention is to prevent this spreading of the rails and consequently reduce the number of wrecks on railways.

My invention also has as one of its objects to lessen the cost of construction and maintenance of a track. While the metal ties made in accordance with the present invention may cost more than wooden ties, when the extra expenses incident to the use of the wooden tie, including spikes, chairs, tie-plates, ballast and cost of labor in adjusting said separate devices and extra thickness of ballast, are considered, and also the much greater durability of the metal tie over the wooden one, it will be seen that the metal tie is much cheaper in the long run, as well as a real necessity in order to prevent accidents.

The invention will be hereinafter described in connection with the accompanying drawings, which constitute a part of this specification, and then more specifically defined in the claims at the end of the description.

In the accompanying drawings, wherein

similar reference characters are used throughout the various views to designate corresponding parts:—Figure 1 is a plan view of a section of track, illustrating how the same is laid with my improved ties. Fig. 2 is a side elevation to illustrate the preferable mode of supporting the track or rails when attaching the ties. Fig. 3 is a longitudinal section of one of the ties having inwardly extending tongues and hereinafter referred to as the “gage-ties.” Fig. 4 is a similar section of one of the ties having outwardly extending tongues and hereinafter called “key-ties.” Fig. 5 is a transverse section of a tie drawn to a larger scale, the ballast of the track being indicated in dotted lines. Fig. 6 is a perspective view of one end of one of the gage-ties. Fig. 7 is a similar view of one end of one of the key-ties. Fig. 8 is a sectional view taken transversely of the rail and longitudinally of the tie, showing on an enlarged scale how a separable clamp may be applied to the tie, although it should be distinctly understood that such separable fastening is not necessary and need only be used in case of accidental injury to the tie and the rail must be temporarily secured to such injured tie until it can be removed and a new one substituted. Fig. 9 is a plan view showing the same application of the separable clamp, and also, in dotted lines, the use of a similar clamp on the opposite side of the rail. Fig. 10 is a plan view of a modified form of track in which the gage-ties and key-ties are laid in pairs instead of alternately, as in Fig. 1, and Fig. 11 is a plan view of a portion of track, illustrating how the gage-ties may be removed from the rails without separating the rails at their joints.

As already intimated, the invention contemplates the use of gage-ties A and key-ties B, one being exactly like the other in size and shape and differing from one another simply in the location and facing of the rail-overlapping tongues and rail-abutting shoulders for fastening the rails to the ties.

Each tie is made of a single piece of sheet metal, preferably steel, having a flat top 12 and downwardly turned side and end flanges 13 and 14, respectively. The inclination of these flanges with respect to the top of the tie may be varied or they may be at any desired angle, and the end flanges may be arranged at a different angle and be of a different length than the side flanges, if desired.

The gage-ties A have two inwardly extending tongues a cut and pressed up from the body of the top thereof and adapted to overlap and hold the outer sides of the bases of the rail C, as illustrated in Figs. 1 and 3. Care is taken in forming these

tongues not to make them too wide and thereby weaken the tie, but at the same time they are made amply wide to give them the necessary strength, the width of the top of the tie being considered. It will also be noted that in forming these tongues the face thereof which is presented to and abuts against the edge of the base of the rail is straight, as seen clearly in Figs. 3 and 8, and indicated by the reference character a' . This straight bearing face gives a very firm hold upon the rail and causes the tie to snap into place when adjusted. The bearing faces a' of the two tongues or lugs on the gage-tie are spaced the proper distance apart to give the rails the desired gage when engaged by or fitted below said tongues. At points opposite said bearing faces and spaced therefrom a distance equal to the width of the base of the rail, there are formed shoulders a^2 designed to abut against the inner sides of said rail-bases. These shoulders are formed by pressing up portions of the top of the tie, as best shown in Figs. 3 and 5. The shoulders are straight on their faces which abut against the inner edges of the bases of the rail in order to hold firmly and give the desired snap when put in place. The other faces and top of said raised portion or shoulder are rounded, as at a^3 so that the base of the rail will ride easily over the same preparatory to snapping into place between the flat or straight faces a' and a^2 and below the tongues or lugs a .

The key-ties B are similarly formed with outwardly extending tongues or lugs b having straight faces b' abutting against the edges of the bases of the rails on the inside, and with raised shoulders b^2 having rounded faces b^3 for the same purposes as described in connection with the gage-ties except that the tongues b extend in the opposite directions from the corresponding lugs a , and the shoulders b' face in the opposite direction from the shoulders a' , so that the inner sides of the bases of the rails are overlapped and held by the tongues of the key-ties while the outer edges of the bases of said rails are overlapped and held by the tongues of the gage-ties. It will be understood that the bearing faces b' of the tongues of the key-ties are spaced apart the proper distance to hold the rails firmly against the bearing faces a' of the tongues of the gage-ties when both kinds of ties are in place.

When laying a new track with my ties, the rails C are preferably supported upon blocks D, see Fig. 2. The gage-ties are then placed in position with their tongues overlapping the outer sides of the bases of the rails, after which the key-ties are introduced in an inclined position, as shown in Fig. 1, and turned to the proper right angle position with respect to the rails, the tongues on

said key-ties taking over the inner sides of the bases of the rails and forcing the said rails to proper gage as determined by the spacing of the tongues on the gage-ties. In 5 thus applying the key-ties, it will be observed that the bases of the rails ride easily over the rounded faces of the raised shoulders and snap into place with the bearing faces of said shoulders abutting against the 10 outer edges of the bases of the rails. After the ties are attached to the rails, the track is lowered onto the ballast by removing the blocks D, and the first train passing over the line will force the flanges of the ties down 15 into the ballast E as indicated in Fig. 5. The embedding of these flanges in the ballast prevents either lateral or endwise movement or shifting of the ties and also causes an air cushion to be formed below each tie 20 which cushion adds to the elasticity of the roadbed as hereinbefore explained.

When it is desired to remove one of the gage-ties from a laid track, it is only necessary to take out two or three of the key-ties, 25 which can readily be done by turning them to an inclined position, slide the gage-ties along the rails far enough to leave a section of the rails sufficiently long to permit of springing said rails inward slightly, which 30 may be done by use of the tool illustrated in Fig. 11, whereupon the gage-tie sought to be removed will drop off of the rails. The tool I have shown for this purpose consists of two hook-shaped plates 18 adapted to engage 35 the outer sides of the bases of the rails, two rods 19 connected to said plates 18 and extending inwardly toward each other, the inner end portions of said rods being screw threaded, and a turn-buckle 20 engaging the 40 inner ends of said rods. It is obvious that by turning the turn-buckle in one direction, the hook-shaped plates 18 and rails engaged thereby will be drawn inward as desired.

In some instances, as on sharp curves, it 45 may be preferred to lay the gage-ties and key-ties in alternate pairs, as illustrated in Fig. 10, but as a rule said ties are laid singly in alternation as shown in Figs. 1 and 2.

Perforations or holes 15 may be formed 50 in the ties, as illustrated in Figs. 8 and 9, to provide for attaching separable clamps 16 when necessary or desirable, as in case of accident occasioned by a broken axle and resulting in an unavoidable fracture, such 55 clamps being secured by bolts 17 passed through the holes 15, but the provision for these separable fastenings is not essential to the present invention, as previously stated, and this should not be taken in any 60 sense to modify the statement that I have provided a one-piece tie capable of attachment to the rails of a track without any separable fastening means.

It will be observed that my tie is very 65 simple in construction and is adapted to be

stamped out of a sheet metal at a single operation, so that it can be manufactured at a very low cost and great saving of time as compared with the majority of metal ties heretofore known.

The minimum weight of my tie, considered with its strength and shape, as well as its integral rail-fastening devices capable of holding both rails of a track, at once appeal to railroad engineers.

Having thus described my invention, what I claim as new and desire to secure by Letters Patent of the United States is:—

1. A one-piece sheet-metal tie having a tongue for holding one side of the base of a rail, and a shoulder pressed up from the top of the tie and arranged directly opposite the tongue for engaging the edge of the other side of the base of the rail, said shoulder having a straight face presented to the edge of the base of the rail and its upper surface rounded laterally for guiding the rail-base into position substantially as described.

2. A one-piece tie having rail-holding 90 tongues to overlap one edge of each of the two rails of a track, said tie also having means arranged at the sides of said tongues for attaching a separate clamp for holding the rail to the tie when necessary or desirable.

3. A one-piece tie having rail-holding 95 tongues to overlap one edge of each of the two rails of a track, and shoulders to abut against the opposite edges of the rails from 100 those which are overlapped by said tongues, said tie also having means arranged at the sides of said shoulders for attaching a separate clamp for holding the rail to the tie when necessary or desirable.

4. A one-piece tie having rail-holding 105 tongues to overlap one edge of each of the two rails of a track, and shoulders to abut against the opposite edges of the rails from those which are overlapped by said tongues, 110 said tie also having means arranged at the sides of said tongues and shoulders for attaching separate clamps for holding the rail to the tie at either or both sides of said rail when necessary or desirable.

5. The combination with one-piece sheet-metal gage-ties, each having a substantially flat top and downwardly turned side and end flanges to engage the ballast of a roadbed, the top of each of said gage-ties having inwardly extending tongues for overlapping and holding the outer edges of the bases of the two rails of a track to proper gage, of key-ties, each made of one piece of sheet-metal shaped like the gage-ties, the 120 top of each key-tie having outwardly extending tongues for overlapping and holding the inner edges of the bases of the rails as and for the purpose described.

6. The combination with one-piece sheet-

metal gage-ties, each having a substantially flat top and downwardly turned side and end flanges to engage the ballast of a roadbed, the top of each of said gage-ties having 5 inwardly extending tongues for overlapping and holding the outer edges of the bases of the two rails of a track to proper gage, of key-ties, each made of one piece of sheet-metal shaped like the gage-ties, 10 the top of each key-tie having outwardly extending tongues for overlapping and holding the inner edges of the bases of the rails with their outer edges firmly in

engagement with the tongues of the gage-ties, both kinds of ties having raised shoulders facing their respective tongues and designed to engage the edges of the opposite sides of the bases of the rails from those overlapped by the adjacent tongues. 15

In testimony whereof I have signed my 20 name to this specification in the presence of two attesting witnesses.

WILLIAM H. ALEXANDER.
